DESIGN FOR A SHIRT

William R. Seymour, Santa Monica, Calif., assignor to Cohn-Goldwater Manufacturing Co., Los Angeles, Calif., a corporation of California

Application February 5, 1940, Serial No. 90,035

Term of patent 3½ years

To all whom it may concern:

Be it known that I, William R. Seymour, a citizen of the United States and residing at Santa Monica, in the county of Los Angeles, and State of California, have invented a new, original, and ornamental Design for a Shirt, of which the following is a specification, reference being had to the accompanying drawing, forming part thereof.

Fig. 1 is a front elevational view of a shirt, showing attached tie member hanging free; Fig. 2 is a corresponding view showing attached tie member folded over and Fig. 3 is a rear elevational view showing attached tie member which forms also the collar, all showing my new design.

I claim:

The ornamental design for a shirt, as shown.

WILLIAM R. SEYMOUR.
